[57] **CLAIM**

The ornamental design of an insulated cover for a backflow preventing water valve, as shown and described.

DESCRIPTION

FIG. 1 is a perspective view taken from the front, bottom and left side of an insulated cover for a backflow prevention water valve showing my new design;

FIG. 2 is a front elevational view thereof;

FIG. 3 is a cross sectional view taken along line 3—3 of FIG. 2;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.
